UNITED STATES PATENT OFFICE

OTTO HENNING, OF ST. LOUIS, MISSOURI, ASSIGNOR TO CARTER CARBURETOR CORPORATION, OF ST. LOUIS, MISSOURI, A CORPORATION OF DELAWARE

CARBURETOR

Application filed September 24, 1930. Serial No. 484,080.

This invention relates to carburetors, and more particularly to carburetors of the down-draft type.

It is an object of the invention to produce a new and improved device of this character for efficiently vaporizing and proportioning the fuel mixture for an internal combustion engine.

It is a further object of this invention to produce a new and improved downdraft carburetor which will thoroughly atomize the fuel delivered to an internal combustion engine without substantially restricting the amount of fuel mixture which may be drawn into the engine by a given suction.

Another object of the invention is to so arrange the elements of the carburetor that boiling of the fuel will be substantially prevented. The importance of this object is emphasized in installations in which the intake and exhaust manifolds are both on the same side of the motor and in which the down-draft carburetor is necessarily mounted directly above the hot exhaust manifold.

Other objects of this invention will appear from the accompanying description which, taken in connection with the accompanying drawings, is such a full, clear, and complete explanation of the device as to enable any mechanic skilled in the art to make and use the invention.

Referring to the drawings:

Figure 1 is a sectional elevation of a carburetor constructed in accordance with my invention.

Figure 2 is a side elevation of the carburetor shown in Figure 1 with parts broken away and others shown in section. The view is taken from the side opposite to the position shown in Figure 1.

Figure 3 is a rear elevation of the carburetor shown in Figures 1 to 3 with parts broken away and others shown in section.

Figure 4 is an end elevation looking into the air horn, parts being broken away for clearer illustration of others.

Figure 5 is a plan view of the carburetor shown in Figures 1 to 4, a portion of the top cover being cut away to more clearly illustrate some of the parts.

Figure 6 is an inverted plan view of the carburetor shown in Figures 1 to 5.

Figure 7 is a diagrammatic view for more clearly illustrating the location and arrangement of some of the parts.

Figure 8 is a diagrammatic view showing the general arrangement of certain parts and passageways of the carburetor.

Figure 9 is a detail view of the pump nozzle.

The reference numeral 1 indicates a body member having a flange 2 by means of which it may be attached to the intake manifold of an internal combustion engine. The body has a comparatively large chamber 3 formed therein to which air is supplied from the air horn 4. At the top of the body member is a seat 5 upon which is mounted a bowl supporting member 6.

At the lower end of the air chamber 3 is a downwardly extending Venturi portion 7 terminating in the mixing chamber 8 which also serves as a discharge passageway for the carburetor, the discharge being controlled by a conventional throttle 9 mounted on a shaft 75 which is controlled by the operator.

The bowl support is attached to the body of the carburetor by any suitable means, such as screws 11, and the carburetor is connected to some suitable source of fuel supply by means of an elbow 12 which is threaded into the bowl support 13, as shown.

A downwardly extending passageway 14 in the bowl support is threaded to receive a needle seat 15 carrying a needle valve 16 to control the flow of fuel into the carburetor. The needle valve is operated by a float 17 pivoted to the bowl support at 18, and the fuel is accordingly maintained at a constant level in the bowl approximately at line A. 90

The bowl support has a downwardly extending portion 19 which is internally threaded at 20 to receive a combined bowl retaining nut and nozzle base 21, which nut, when screwed into position, first forces the upper rim of the bowl 22 against the gasket 23 and then seals the bottom of the bowl against the end of the extension 19, it being understood that the extension 19 is slightly shorter than the depth of the bowl. The interior of the nut 21 is bored at 24 to form a fuel passageway which registers with the passageway 25 and the extension 19.

A cross bore 26 is formed in the bowl support at the upper end of the passage 25 and communicates with the discharge outlet of an upwardly extending partition member 27 which is threaded into a well 28 from the lower end of the extension 19. The tubular member 27 divides the well 28 into two por- 110

tions, one being an inlet portion surrounding the tube 27, and the other being an outlet portion within the tube 27.

The well is of larger diameter than the member 27, as indicated, and an air passage 29 having a calibrated inlet 30 is connected to the upper and outer part of the well 28. A plurality of accelerating holes 31 are placed along the member 27 and calibrated to permit the passage of suitable quantities of air successively as the holes are uncovered by the suction. The well 28 is fed through a cross passage 32 which communicates with the interior of the bowl 22 through a calibrated passageway 33. A passageway 34 connects the upper part of the passage 25 with the inside of the bowl above the fuel level.

The calibrated passageway 33 is regulated by a metering rod 35 having one or more steps 36 of different size so that by adjusting the metering rod 35 longitudinally in the passage 33, different rates of fuel flow may be obtained. A sealing device 37 substantially prevents the leakage of air around the metering rod 35 where it passes through the opening 38 in the bowl support 6.

The air pressure within the bowl is partially controlled during operation by a vent 39 communicating with the tube 40 which terminates at a central point in the air stream as it flows into the carburetor. It will be understood that the motion of the air at this point is rapid, but not so rapid as it is at the throat of the venturi 7.

The nozzle of the carburetor comprises an inner shell 41 and an outer shell 42 attached to the jet base 21. The ends of both of the shells are rounded off and closed, except for the perforations 43 in the inner shell and 44 in the outer shell. These openings serve as vaporizing discharge passages for the fuel and air which is bled into the fuel through the passages 29 and 34. It will be understood that the fuel is already in the form of a spray or emulsion as it flows through the passages 25 and 24, and the rapid discharge through the openings 43 and 44 serves to substantially atomize or vaporize the liquid.

For low speed operation, a port 46 is provided in the wall of the mixing chamber 8. The edge of the throttle, when in closed position, divides the port into two parts: one exposed to the near-atmospheric pressure above the throttle 9, and the other exposed to the comparatively high suction created by the engine. The operation and arrangement of this port is well known to the art, being that described in the patent to W. C. Carter, No. 1,207,134, patented December 5, 1916.

The fuel is supplied to the idle or low speed port 46 through passageways 47 and 48, tube 49, passages 50 and 51, and nozzle 52 from the bowl 22. The fuel entering the nozzle 52 from the bowl through the port 53 is first

metered by the size of the cross bore 54 in the nozzle, and the suction is controlled by the size of the fixed air bleed 55 and the adjustment of the screw 56 which cooperates with the seat 57 to admit more or less air to the idle passage through a port 58. It should be noted that the air bleed 55 is above the float level so that no siphoning can be set up when the carburetor is not in operation.

The throttle shaft 10 is operated by a crank 59 from any suitable source, and a second crank 60 is made integral with the crank 59. A link 61 is connected to the crank 60 and is pivoted at its upper end to a rocker 62 rigidly connected to a shaft 63 which is mounted on bearings 64 which are integral with the bowl support 6.

The metering rod 35 is connected to shaft 63 by a crank member 65, the connection being such that the smaller step 36 of the metering rod is drawn into the passage 33 during the latter part of the opening movement of the throttle. In other words, the maximum richness of the mixture occurs at wide open throttle. At the end of the shaft 63, opposite the crank 65, a crank 66 is connected, and a link 67 connects the crank 66 with the shaft 68.

A cylinder 69 is formed in the body member, and since the body member is of cast or malleable iron and, therefore, unsuitable for use as a wearing surface without oil lubrication, a tubular lining 70 of brass is inserted. The fuel used in carburetors of this type have little lubricating value, but a brass and leather contact may be used with good success when soaked in the fuel. A piston 71 is slidably mounted in the lining of the cylinder and rigidly connected to the shaft 68 in such a manner that the piston would be moved downwardly upon an opening movement of the throttle.

The fuel for the pump is drawn from the bowl through a tube 72 fixed in the member 6 and terminating at its lower end in the bowl below the fuel level. A gravity operated ball check 73 is provided to prevent the return flow of fuel. The tube 72 connects through a cross passage 74 with a downwardly extending passage 75 and a cross passage 76 leading into the lower part of the cylinder of the pump. The other end of the passage 76 terminates in an upwardly extending bore 77 in which is fixed a gravity operated ball check 78 forming an outlet check valve of the pump. Fuel from the pump is discharged through the ball check 78 into a chamber 79, as indicated in Figure 3. The upper end of the chamber 79 is closed by a plug 80, and the lower end of this chamber is threaded to receive a nozzle 81 which discharges into the venturi 7.

The nozzle is provided with a highly restricted portion 82 which serves to discharge the fuel in a fine stream into a comparatively

large tube 83. A small port 84 is formed just beyond the outlet of the restricted passage 82 and serves to admit air and vaporize the fuel discharged by the pump and also to prevent fuel being continually drawn through the pump by high suction at the inlet of the venturi 7. In other words, the opening 84 breaks the suction.

A suitable dust cover 85 is mounted on the upper side of the bowl retaining member 6 and serves to protect the shaft 63 and associated parts from dust or other injury. A suitable screw 86 holds the cover in place. It will be understood that the cover may be vented so that the admission of air to the port 30 will not be interfered with.

For starting purposes, a choke valve 87 is slidably mounted on the outer shell 42, and this valve is provided with an annular recess 88 which receives the inturned ends of a yoke 89 which is mounted on the choke shaft 90. The shaft 90 is suitably journaled in the walls of the body member, and a crank 91 is mounted on the shaft so that it may be operated from any convenient source.

A spring 92 normally holds the choke in open position, as indicated in Figures 1 and 7. A relief valve 93 is mounted in the choke valve to control the by-passes 94 which serve to admit air through the choke valve the instant after the engine starts. A spring 95 yieldably holds the valve 93 in closed position so that the suction of the engine which is developed as soon as it starts to run under its own power will be sufficient to overcome the pressure on the spring 95 and permit the valve 93 to open.

The choke valve may, if desired, be interconnected with the throttle by means of a link 96 pivoted at 97 to the crank 91 and at its other end to the crank 98 which is loosely mounted on the throttle shaft 10. A projection 99 on the crank 98 is so mounted with respect to the collar 100 and screw 101 that the closing movement of the choke causes the throttle to be slightly open. It will be understood that the screw 101 is threaded into the collar 100, and these two members are firmly fixed to the shaft by tightening the screws.

Since the opening movement of the throttle (with particular reference to Figure 7) is in a clock-wise direction, the throttle may be opened or closed without moving the choke, as long as the choke is in open position. Since the connection of the throttle and choke form no part of the present invention, no further description is believed to be necessary.

The operation of the device is as follows: When the engine is to be started cold, the lever 91 is operated to move the choke valve 87 downwardly against the throat of the venturi 7, thereby substantially closing the main air entrance to the carburetor. The

suction developed by the engine acts directly on the fuel jets and draws a very rich mixture of gasoline and air down through the nozzle and through the outlets 43 and 44. Some fuel may also be drawn through the idle passage under these conditions. As soon as the engine starts to run under its own power, the increased suction causes the valve 93 to open, thereby permitting enough air to flow through the carburetor to form a burnable mixture with the comparatively large amount of fuel that enters when the choke is closed. After the engine is started, the choke valve 87 may be gradually opened to the position shown in Figure 1 as the engine warms up.

With the throttle in closed position, a high suction on the lower side of the throttle valve 9 is built up and fuel is drawn through the passages 53, 54, and 51 up to the point where air is admitted through the air bleed 55. From this point an emulsion of fuel and air is drawn through the cross passage 50 and the tube 49 down to the idle screw 56 where further vaporization is obtained by air entering at that point. The fuel and air then flows through passages 48 and 47 to the ports 46, at which time final vaporization occurs with air entering on the upper side of the port. Obviously, as the throttle is gradually opened, the amount of air entering at 46 is restricted, and the amount of fuel mixture drawn through 47 is increased.

As the suction in the mixing chamber is increased by opening the throttle, suction around the nozzle begins to draw air through the discharge outlet 44, and fuel is then drawn from the fuel bowl through the passage 33, the accelerating well 28, up through the cross passage 26 and down into the nozzle. Some air enters at 34 and passes, with the fuel, down through the passages 25 and 24 and assists in vaporizing the fuel as the mixture passes through the openings 43 and 44. Air also enters the mixture through the upper opening 30, forming an outside air bleed for the well, in addition to the inside air bleed 34 for the nozzle, the provision of the outside air bleed to the accelerating well being made because it is not desired to suddenly withdraw additional air from the bowl during acceleration, for this would restrict the flow from the main nozzle and cause a leanness of the mixture at a time when additional richness is most desired.

It will be understood that the suction at the throat of the venturi is greater than the suction at the inlet of the conduit 40. Accordingly, air will flow into the upper part of the mixing chamber through the conduit 40 and, after circulating through the upper part of the float chamber 22, will be discharged through the opening 34 into the nozzle. A very beneficial cooling effect is thereby secured which is important in a downdraft

carburetor, because carburetors of this type are mounted just on top of the intake manifold and also on top of the exhaust manifold which becomes extremely hot in operation and trouble from boiling of the fuel is often experienced.

It will be understood that as the rate of flow through the carburetor is increased, suction on the nozzle is increased which tends to draw in more air through the inlets 34 and 30. Air drawn from the fuel bowl through the passageway 34 tends to lower the pressure in the bowl and, therefore, to restrict the discharge of fuel through the passage 33. If all the air necessary for primary mixing with the fuel in the conduits 25 and 24 (including the air used for discharging the well 28) were taken direct from the fuel bowl through the passageway 34, the restricting effect during acceleration and at higher suction would be too great, and the mixture would be leaned out to an undesirable extent. For that reason, the air for discharging the well is taken through the air bleed 30 which opens to the atmosphere.

It is found to be desirable to vary the pressure in the fuel bowl in accordance with the velocity of the air stream flowing through the air horn in addition to the variation of the bowl pressure in accordance with the fuel flowing through the passages 24, 25, and 26, and the tube 40 accomplishes this object for the reason that it terminates at the point of highest velocity in the air stream entering the carburetor so that a suction is built up in proportion to the speed of this air stream.

Another important function of the tube 40 is to permit a constant flow of air through the upper port of the fuel bowl, to cool the fuel and carry off vapors.

Upon opening the throttle valve, fuel contained in the pump cylinder 70 is discharged through the passage 76, the check valve 78, the jet 82, and the mixing tube 83 toward the throat of the venturi 7. The fuel is sprayed in a fine stream through the passage 82 to mix with air entering the port 84 so that it is partially vaporized before its discharge into the main venturi 7. As will be noted from the drawings, the discharge nozzle of the outlet 83 is adjacent the venturi 7 at a point in the mixing conduit which is restricted and at which high suctions and high velocities prevail. When the carburetor is operated near full capacity, the suction developed in the outlet of the nozzle 83 is likely to unseat the inlet and outlet check valves of the pump and cause a continuous flow of fuel to flow through the pump and out of the nozzle. The opening 84 is very effective in counteracting this, for this opening is at a point in the mixing conduit at which it is much less restricted than at the outlet of the nozzle 83. The velocities and

suctions are accordingly much lower, and the suction in the discharge nozzle 83 may be said to be broken to such an extent that it will not cause the pump to pull over at high suction.

Upon closing the throttle valve, the link 61 rocks the shaft 63 in a clockwise direction (see Figure 2) moving the plunger 71 upwardly and drawing fuel into the pump through the check valve 73.

I claim:

1. In a downdraft carburetor, means forming a main air passageway, a downwardly directed venturi having a substantially vertical axis in said passageway, means forming a constant level fuel chamber, a downwardly extending nozzle connected with said constant level chamber and supplied with fuel therefrom, said nozzle comprising an inner shell and an outer shell, said outer shell having a discharge opening at its lower end within said venturi, said inner shell having a plurality of discharge openings and discharging into the space between said shells.

2. In a downdraft carburetor, means forming a constant level fuel chamber, means forming a mixing conduit, a nozzle for discharging fuel into said mixing conduit, a supply conduit for supplying fuel from said constant level chamber to said nozzle, said supply conduit including a well supplied with fuel by gravity from said fuel chamber through a calibrated orifice, said well having a partition separating it into inlet and discharge portions, a plurality of vertically spaced openings connecting said inlet and discharge portion, an air bleed from said constant level chamber into said supply conduit, and a secondary bleed leading from the atmosphere to a part of said fuel supply conduit.

3. In a downdraft carburetor, means forming a constant level fuel chamber, means forming a mixing conduit, a nozzle for discharging fuel into said mixing conduit, a supply conduit for supplying fuel from said constant level chamber to said nozzle, said supply conduit including a well supplied with fuel by gravity from said fuel chamber through a calibrated orifice, said well having a partition separating it into inlet and discharge portions, a plurality of vertically spaced openings connecting said inlet and discharge portion, an air bleed from said constant level chamber into said supply conduit, and a secondary bleed leading from the atmosphere to the inlet portion of said well.

4. In a downdraft carburetor, means forming a constant level supply chamber, means forming a mixing conduit, a nozzle for discharging fuel into said mixing conduit, a supply conduit for supplying fuel from said constant level chamber to said nozzle, means for varying the pressure in said fuel supply chamber in accordance with the flow in said

supply conduit, and other means for varying the pressure in said fuel supply chamber in accordance with the rate of flow through said mixing conduit.

zle, said supply conduit having a fuel inlet below the fuel level in said constant level chamber and an air inlet in said constant level chamber at a point above the fuel level, and said constant level supply chamber having an air inlet from a point of greater pressure than that existing in the venturi, whereby a constant flow of cooling air through the constant level chamber will be produced. 70

5 5. In a downdraft carburetor, means forming
a mixing conduit having an air inlet,
means forming a constant level fuel supply
chamber, a nozzle discharging into said mix-
ing conduit, a supply conduit for conveying
10 fuel from said constant level chamber to said
nozzle, a throttle valve in said mixing con-
duit, means for controlling the flow of fuel
to said nozzle in accordance with the position
of said throttle, means for affecting the pres-
15 sure in said constant level chamber in accord-
ance with the rate of flow of fuel to said noz-
zle, and other means for affecting the pres-
sure in said constant level chamber in accord-
ance with the rate of flow through said air
20 inlet.

constant level chamber will be produced. 75
10. In a downdraft carburetor, means forming a mixing conduit, a downwardly extending venturi in said mixing conduit, means forming a constant level fuel chamber, a nozzle discharging at the throat of said venturi, a supply conduit for supplying fuel from said constant level chamber to said nozzle, said supply conduit having a well therein, said well being divided into inlet and outlet portions by a perforated wall, the inlet portion of said well being connected to the lower part of said constant level fuel chamber through a restricted orifice, the upper part of the inlet portion of said well having an opening through which air may be admitted by suction in accordance with the degree to which said perforation or perforations are uncovered by the fuel level, and a passageway having an inlet above the fuel level in said constant level chamber and having an outlet between the outlet of said nozzle and said well. 80 85 90 95

20 means forming a mixing conduit, a downwardly extending venturi in said conduit, a nozzle having its axis substantially co-incident with that 25 of the venturi and discharging into said venturi, a choke valve slidably mounted on said nozzle for controlling the flow of air through said venturi, said choke valve having a by-pass therein, and a downwardly opening 30 check valve controlling said by-pass.

11. In a downdraft carburetor, means forming a mixing conduit, said mixing conduit having an inlet and an outlet, a throttle valve controlling said outlet, a restricted portion in said conduit between said throttle valve and said inlet, a main fuel supply device constructed and arranged to supply fuel to said conduit at a point adjacent said restricted portion, an accelerating pump connected to and operated by said throttle, said pump having a discharge nozzle for delivering fuel to said conduit at a point adjacent said restricted portion, and means for admitting air to said nozzle at a point substantially anterior to said restricted portion, whereby the tendency of said pump to discharge continuously at high suction will be reduced. 100 105 110

8. In a downdraft carburetor, means forming a mixing conduit having an air inlet, means forming a constant level chamber, a nozzle connected with said constant level chamber to discharge fuel to said mixing conduit, a control conduit terminating in
45 said mixing conduit at the center of the air stream therein, said control conduit being connected to said constant level chamber above the level of fuel therein to vary the pressure in said constant level chamber in
50 55 accordance with the rate of flow through said mixing conduit, and means for affecting the pressure in said constant level chamber in accordance with the rate of flow to said nozzle.

12. In a downdraft carburetor, means forming a mixing conduit, a venturi in said mixing conduit, a throttle valve in said mixing conduit below said venturi, a constant level fuel chamber, a main fuel supply device for delivering fuel from said constant level chamber to said mixing conduit, substantially at the throat of said venturi, an accelerating pump receiving fuel from said constant level chamber and having a discharge outlet in said mixing conduit at a point anterior to said venturi, and means for admitting air to said discharge outlet at a point anterior to its point of discharge. 115 120 125

In testimony whereof, I affix my signature.
